Primary Examiner — Robin V Webster*Assistant Examiner* — James Thorn, Sr.(74) *Attorney, Agent, or Firm* — Foley & Lardner LLP(57) **CLAIM**

I claim the ornamental design for a table, as shown and described.

DESCRIPTION

FIG. 1 is a top perspective view of an embodiment of the claimed design;

FIG. 2 is another top perspective view of the embodiment shown in FIG. 1;

FIG. 3 is a top plan view of the embodiment shown in FIG. 1;

FIG. 4 is a bottom plan view of the embodiment shown in FIG. 1;

FIG. 5 is a first side view of the embodiment shown in FIG. 1;

FIG. 6 is a second side view of the embodiment shown in FIG. 1;

FIG. 7 is a third side view of the embodiment shown in FIG. 1; and,

FIG. 8 is a fourth side view of the embodiment shown in FIG. 1.

The ornamental design which is claimed is shown in solid lines in the drawings. The broken lines in the drawings are for illustrative purposes only and form no part of the claimed design.
